UNITED STATES PATENT OFFICE

PAUL GREVILLE HUDSON, OF CARLISLE, ENGLAND, ASSIGNOR TO CALLARD & BOWSER,
LIMITED, OF LONDON, ENGLAND

DESIGN FOR A BOX

Application filed September 8, 1932, Serial No. 44,767, and in Great Britain June 10, 1932. Term of
patent 14 years.

To all whom it may concern:

Be it known that I, PAUL GREVILLE HUDSON, of 12 Chatsworth Square, Carlisle, Cumberland, England, have invented a new, original, and ornamental Design for a Box, of which the following is a specification, reference being had to the accompanying drawing, forming a part thereof, in which the figure is a perspective view of a box.

I claim:—

The ornamental design for a box substantially as shown.

In witness whereof I have hereunto signed my name.

PAUL GREVILLE HUDSON.
